UNITED STATES PATENT OFFICE

FRANK COATES, OF CLEADON, AND JAMES MIRREY, OF EAST BOLDON, ENGLAND,
ASSIGNORS TO A. REYROLLE & COMPANY LIMITED, OF HEBBURN-ON-TYNE, ENGLAND, A COMPANY OF GREAT BRITAIN

ELECTRIC SWITCH GEAR

Application filed July 6, 1926, Serial No. 120,860, and in Great Britain August 10, 1925.

This invention relates to electric switch gear and has for its object to provide a simple and convenient form of operating mechanism for a group of oil switch panels.

5 According to the present invention means are provided for selectively operating two or more oil-immersed switches from an electric motor or other driving unit common to all the switches. Thus each switch is provided with its own actuating mechanism which can be brought by the selecting means into operative engagement with the driving unit or with a common driving member energized thereby.

15 Preferably energy received from the electric motor or other driving unit is stored in a spring or other device and is released therefrom for the selective operation of the switches. There may be one energy-20 storing device common to all the switches, or alternatively each switch may have its own energy-storing device, all the devices being energized from the common driving unit.

25 The invention may be carried into practice in various ways but some alternative arrangements according thereto are illustrated by way of example in the accompanying drawings, in which

30 Figures 1-4 respectively show a side elevation, a front elevation, a plan (partly in section on the line 3-3 of Figure 1) and a detail view of one arrangement,

Figures 5 and 6 illustrate a modification 35 of this arrangement,

Figures 7 and 8 respectively show a front elevation and a plan of an alternative arrangement,

Figures 9 and 10 respectively show a front 40 elevation (partly in section) and a section on the line 10-10 of Figure 9 of a further arrangement,

Figures 11 and 12 illustrate a further alternative arrangement, and

45 Figures 13 and 14 are diagrammatic views indicating the general arrangement of the switchgear and the electrical circuits.

In all the arrangements illustrated, each of the metal-clad oil-immersed switches is 50 provided with actuating mechanism comprising

ing a movable rack engaging with a pinion on a shaft, rotation of which against the action of a spring acts to close the switch, the spring being provided for the purpose of opening the switch when separate tripping mechanism is operated. The details of this arrangement will be described later with reference to Figures 13 and 14. It will be understood however that other forms of actuating mechanism may be employed.

55 In the arrangement of Figures 1-4 the power necessary for closing the switches is supplied from an electric motor A through reduction gearing A¹ A² A³ to a gear wheel B carried on a sleeve B¹ which can be coupled (by means of a magnetic or other electrically-operated clutch B²) to a main driving shaft C common to all the switches. The clutch B² is preferably operated electrically 60 by means of a governor (indicated at A⁴) on the shaft of the motor A, so that the sleeve B¹ is clutched to the driving shaft C when the motor attains full speed.

65 The main driving shaft C carries a number of gear wheels C¹ (one for each switch) which mesh with other gear wheels C² respectively forming part of individual operating mechanisms for the switches. These individual mechanisms are similar to one another, and for the sake of simplicity only one such mechanism is shown in the drawings. This mechanism comprises in addition to the gear wheel C², a slotted link D pivoted eccentrically (at D¹) to a disc C³ carried by the gear wheel. A rack E mounted to slide 70 vertically on guide rollers E¹ carries a pin E² which engages in the slot D² of the link D. This rack E forms the primary member of the switch-actuating mechanism and engages 75 with a pinion E³ on the switch-actuating shaft E⁴. Thus when the driving shaft C is rotating the link D is reciprocated past the pin E² and the slot D² is made of such a length that normally the pin will not be moved.

80 85 90 95 100 Pivoted at F¹ to the end of the link D is a catch lever F (see Figure 4) controlled by a solenoid F². This catch lever F is so arranged that it will move over (when the solenoid is energized) and cover the lower part

of the slot D^2 , thus reducing the length of the slot. The catch lever is normally held in its inoperative position by means of a spring F^3 . Means such as a doubly threaded nut D^3 are preferably provided whereby the length of the link D may be adjusted. If desired, a spring D^4 may be provided between the link D and its pivot D^1 to cover small inaccuracies in adjustment.

10 In operation when it is desired to close a selected switch, the motor A is started and run up to full speed. Before full speed is reached the solenoid F^2 associated with the selected switch is energized and moves its catch lever F over to close part of the slot D^2 in the link D . When full speed is reached, the motor clutch B^2 is closed, and the driving shaft C is rotated to drive the gear wheels C^1 C^2 and cause the slotted links D to reciprocate. In the case of the selected switch, the reciprocation of the link D and its catch lever F will move the pin E^2 and the rack E and will thus drive the actuating mechanism to close the switch. For all the other switches 15 the reciprocation of the slotted links D will have no effect on the pins E^2 and these switches will therefore remain unaffected. When the selected switch has been closed, its solenoid F^2 and the motor clutch B^2 are de- 20 energized and the motor is stopped. The whole mechanism is now ready for the operation of another switch when required. The opening of the switch is effected by tripping mechanism in the usual manner, and, apart 25 from the fact that it will bring the rack E and the pin E^2 back into its original position relative to the slotted link D , it will have no effect on the closing mechanism described.

A modification of this construction is ill- 30 ustrated in Figures 5 and 6. In this modification the arrangement of the motor and gearing is the same as that in the construction of Figures 1-4 (the same reference letters being employed), with the exception 35 that the magnetic clutch B^2 is dispensed with and the gear wheel B is directly mounted on the main driving shaft C . As before the main shaft C carries a number of gear wheels C^1 meshing with gear wheels G respectively 40 forming part of similar individual operating mechanisms for the switches. The gear wheel G is connected through an electrically-operated clutch to a disc G^1 . Any convenient form of electrically-operated clutch (such 45 for example as a magnetic clutch) may be employed, but as illustrated the clutch G^2 is of the expanding ring type actuated through a collar G^3 and forked lever G^4 by a solenoid G^5 .

60 Pivoted eccentrically at H^1 to the disc G^1 is a slotted link H (which may be provided as in the previous construction with an adjusting nut H^3 and spring H^4). Within the slot H^2 of this link H a pin J^2 engages, which 65 is carried by a rack J movable in guide rollers

J^1 , this rack serving to actuate a pinion J^3 on the switch-actuating shaft J^4 . The slot H^2 in the link H is only half the length of the corresponding slot in the previous construction, and the solenoid-operated catch lever is dispensed with.

In operation when it is desired to close a selected switch, the motor is started and run up to full speed. When full speed it attained the solenoid G^5 associated with the selected switch is energized to operate the clutch G^2 , so that for this switch the rotation of the driving shaft C causes the reciprocation of the link H , which causes the rack J to drive the switch-actuating mechanism and thereby to close the switch. The other switches remain unaffected by the rotation of the driving shaft C . When the switch has been closed, the shaft C continues to rotate for a half-revolution, and the solenoid G^5 is de-energized and the motor is stopped, so that the mechanism is ready for the closing of other switches when required. As in the previous arrangement the tripping of the switch does not affect the closing mechanism apart from the fact that it causes the rack J to move down again until the pin J^2 reaches the bottom of the slot H^2 .

Figures 7 and 8 show a further alternative arrangement. In this instance a motor K is connected through a clutch K^1 operated by a solenoid K^2 to a worm K^3 meshing with a worm wheel K^4 . The shaft K^5 of this worm wheel carries two pinions K^6 which mesh with gear wheels L . Each of the two gear wheels L has eccentrically pivoted to it at L^1 one end of a link L^2 , whose other end is connected through balanced springs L^3 (provided for the purpose of covering small inaccuracies in the length of the link L^2) to a pin L^4 . This pin L^4 passes through a pair of parallel driving bars M , which are common to all the switches. To allow for lack of alignment between the various switches, the driving bars M are preferably made in sections, swivelling connections M^1 being provided between adjacent sections. The parallel bars M are carried between guide rollers (not shown). Thus when the solenoid K^2 is energized the motor K drives the gear wheels L in the direction of the arrow shown in Figure 7 and thus causes the reciprocation of the parallel driving bars M .

The driving bars M have pivoted to them a number of arms N , one for each switch, each arm being moved by a stirrup N^1 controlled by a solenoid N^2 . Thus when the solenoid N^2 is energized, the arm N is lifted from the position shown in dotted lines in Figure 7 into the operative position (shown in full lines), in which its end abuts against the end of a rack N^3 supported on rollers N^4 . This rack N^3 forms the primary member of the switch-actuating mechanism and engages with a pinion N^5 on the switch-actuating shaft N^6 .

In operation, when it is desired to close a selected switch, the motor K is started and run up to full speed, and the solenoid N² associated with the selected switch is energized. The energization of the solenoid N² brings the selected arm N into its operative position, so that when the solenoid K² is energized to close the motor clutch K¹, the driving bars M will be reciprocated and will drive the rack N³ to close the selected switch. The other switches will remain unaffected since the arms N associated with them will reciprocate underneath the corresponding racks without touching them. When the switch has been closed, the mechanism is allowed to run for another half-revolution of the gear wheels L in order to bring the driving bars M back to their original positions, and the solenoids K² and N² are deenergized and the motor stopped. The apparatus is now ready for the closing of other switches when required. As in the previous constructions the only effect on the closing mechanism of opening the switch by means of the usual tripping mechanism is to move the rack N³ back to its original position ready for reclosing.

In the foregoing arrangements the switches are selectively closed by what may be described as direct operation from a motor. In many instances, however, it is preferable to employ the motor for the purpose of setting an energy-storing device, the energy being released from this device when required for the purpose of closing the selected switch. In this case two alternative arrangements may be employed, in one of which a single energy-storing device common to all the switches is employed, whilst in the other each switch is provided with its own energy-storing device, all the devices being set from a single source of power.

Figures 9 and 10 show a convenient arrangement in the case when a single energy-storing device is employed. In this construction an electric motor O, which is preferably provided with an electrically controlled friction brake indicated at O¹, acts through worm reduction gearing O² O³ on a pair of gear wheels O⁴ each provided with cranks O⁵. Each crank O⁵ is provided with a connecting rod O⁶, the two connecting rods being rigidly attached to a cylindrical barrel P¹ containing a spring P. This spring is held between the cover P² of the barrel and a plunger P³ which carries a rod P⁴ passing through the cover P². At its upper end this rod P⁴ is pivoted to a toothed sector Q mounted on a spindle Q¹ carrying a crank Q² connected by a link Q³ to a two-armed lever Q⁴, which is in turn connected to a pair of toggle levers Q⁵ controlled by a further pair of toggle levers Q⁶ actuated by a solenoid Q⁷.

The toothed sector Q meshes with a rack R¹ carried by a pair of parallel driving bars R. These driving bars R are formed in sec-

tions connected together and extend across the whole group of switches, only one section associated with one switch being shown in the drawings for the sake of simplicity. The driving bars R are supported on rollers R² running in fixed guides R³. These driving bars R have pivoted to them a number of arms S, one for each switch. Each arm S can be lifted from an inoperative position into the operative position shown in the drawings by means of a stirrup S¹ actuated by a solenoid S². In the operative position the end of the arm abuts against a rack S³ supported on rollers S⁴ running in guides S⁵, this rack meshing with a pinion S⁶ mounted on the switch-actuating shaft S⁷.

In operation, the spring P is normally maintained compressed (as shown), and when it is desired to close a selected switch, the appropriate solenoid S² is energized to raise its arm S into the operative position. The toggle-actuating solenoid Q⁷ is then energized to break the toggle and thus to release the spring P, which expands and pulls over the toothed sector Q to drive the parallel driving bars R. The movement of the bars R causes the arm S associated with the selected switch to drive its rack S³ and thereby to close the selected switch. The other switches remain unaffected since the arms S associated with them move underneath the corresponding racks and do not touch them. When the selected switch is closed, suitable auxiliary switch mechanism is operated to release the motor brake O¹ and start up the motor O, the solenoids Q⁷ and S² being deenergized. The motor then drives the cranks O⁵ to raise the barrel P¹. This pushes the sector Q back to its original position, the driving bars R also moving back, and the toggles Q⁵ and Q⁶ are reset thus holding the sector Q in this position. Further rotation of the cranks O⁵ into the position shown brings the barrel P¹ down again and thus again compresses the spring ready for further switch-actuation when required. The motor O is stopped and the brake O¹ applied when this position is reached. The opening of the switch by the unusual tripping mechanism will have no effect on this closing mechanism, except for the fact that it will bring the rack S³ back to its original position.

Figures 11 and 12 show an arrangement in which a separate energy-storing device is provided for each switch. In this construction an electric motor T drives through reduction gearing T¹ a driving shaft T² common to all the switches. This shaft T² carries a number of gear wheels T³, one for each switch, and each of these gear wheels meshes with a second gear wheel T⁴ driving a crank arm T⁵, to which is pivoted one end of a slotted link T⁶. The energy-storing device provided for each switch consists of a spring U, which is compressed by movement of a plunger U² in a

cylindrical barrel U^1 , this plunger being connected by a rod U^3 and links U^4 with a pin U^5 engaging in the slot T^7 of the link T^6 .

The slot T^7 is of such a length that normally the link T^6 will slide over the pin U^5 during rotation of the crank arm T^5 without moving the pin. A catch lever T^8 controlled by a solenoid T^9 is pivoted to the link T^6 , and is so arranged that, when the solenoid is energized, it moves to cover part of the slot T^7 . When the catch lever T^8 is thus moved into its operative position, rotation of the crank arm T^5 will cause the pin U^5 to be moved to compress the spring U . The spring is held in the compressed condition by means of toggle levers U^6 connected to a rack U^7 carried by the links U^4 , these toggle levers being controlled by a further pair of toggle levers U^8 actuated by a solenoid U^9 . The rack U^7 meshes with a pinion V on a shaft V^1 carrying a clutch member V^2 provided with a recess V^3 . A second clutch member V^4 , provided with a tooth V^5 cooperating with the recess V^3 , is keyed to the switch-actuating shaft V^6 25 a spring V^7 being provided which tends to hold the two clutch members in engagement.

The drawings show the apparatus in position when the switch has just been closed. As soon as the switch is closed, the solenoid T^9 is energized to move the catch lever T^8 into the operative position, in which it covers part of the slot T^7 , and the motor T is started up for the purpose of compressing the spring U , the toggle mechanisms U^6 and U^8 being reset 30 by the movement of the rack U^7 . During this movement of the rack, the clutch member V^2 rotates through part of a revolution, the tooth V^5 being forced out of the recess V^3 . After the crank arm T^5 has made one complete revolution the motor is stopped and the solenoid T^9 is deenergized. The mechanism remains 35 in this condition until the switch is opened by the usual tripping mechanism. This opening of the switch causes the rotation of the shaft V^6 just far enough to bring the tooth V^5 again into engagement with the recess V^3 . The mechanism is now ready for the reclosing of the switch when required. The closing of the switch is brought about by energizing 40 the solenoid U^9 . This has the effect of breaking the toggles U^6 U^8 and thereby of releasing the spring U to drive the switch actuating shaft V^6 . As has been mentioned the spring 45 is at once reset when the switch has been closed.

Figures 13 and 14 are diagrammatic views of the general arrangement of one of the switches and serve to show one convenient manner in which the rack-operated shaft (referred to in each of the constructions above described) actuates the switch. Figure 13 60 also indicates by way of example the electrical circuits employed with the construction of Figures 9 and 10. It will be clear that

this arrangement of circuits can be readily modified to suit the other constructions.

The three-phase switchgear of the horizon draw-out type shown in Figures 13 and 14 comprises a draw-out portion W which can be moved for example on rollers W^1 relative to a fixed portion W^2 . The fixed portion carries two rows of sockets, three in each row, the sockets W^3 of the upper row being connected respectively to the three busbars W^4 in a busbar chamber W^5 whilst the sockets W^6 of the lower row are connected to a feeder or transformer in the usual manner. The hood W^7 of the draw-out portion W carries two rows of plugs cooperating with these sockets, the plugs of the upper row being respectively connected to the three fixed phase-contacts W^8 of the main switch contained in the oil tank W^9 , whilst the plugs of the lower row are connected to the other three fixed phase-contacts W^{10} , of the main switch. The three movable phase-contacts W^{11} of the main switch are all carried on a bar W^{12} supported on two ropes W^{13} , by which the switch is operated. These ropes W^{13} are connected to the ends of a spindle X carried by lever arms X^1 fixed on a shaft X^2 . The spindle X also carries two short arms X^3 each having a roller X^4 at its end. Each roller X^4 cooperates with a recess 95 in a cam-shaped block X^5 rotatably mounted on a spindle X^6 carried on the ends of cranks X^7 on a shaft X^8 , which is mounted coaxially with the shaft X^2 and is connected through bevel gearing X^9 with a shaft X^{10} . This shaft X^{10} engages through a sliding connection X^{11} , when the draw-out portion is racked in, with the shaft S^7 , part of which is shown in Figure 10 (or with the shaft E^4 of Figures 1-4, or the shaft J^4 of Figures 5 and 6, or the shaft N^6 of Figures 7 and 8 or the shaft V^6 of Figures 11 and 12). This shaft S^7 (or E^4 or J^4 or N^6 or V^6) is mounted on the fixed portion of the gear and is provided with a spring X^{12} which tends to 100 rotate it in a direction to open the main switch. Each cam-shaped block X^5 carries an arm X^{13} which is held in position by means of a toggle mechanism X^{14} . A spring-controlled catch lever X^{15} is provided on one 105 of the crank arms X^7 to cooperate with a fixed stop X^{16} when the mechanism has been moved into the "switch closed" position.

Thus when the shaft S^7 is rotated in the manner previously described for the purpose of closing the switch, its motion is transmitted to the shaft X^8 , which causes the cranks X^7 to push the arms X^3 (the rollers X^4 being at this stage in engagement in the recesses in the cam-shaped blocks X^5 which are held in 115 position by the toggle mechanism X^{14}) and thus to move the spindle X and the ropes W^{13} to close the switch, the lever arms X^1 being held in position with the switch closed by the toggle mechanism X^{14} and by the en- 120 125 130

gagement of the catch lever X^{15} with the stop X^{16} . When the switch is to be opened, tripping mechanism (not shown) acts to lift the catch lever X^{15} and to break the toggle X^{14} thereby allowing the rollers X^4 to move out of the recesses in the cam-shaped blocks X^5 . The switch contacts W^{11} thereupon open under the action of "kick-off" springs (not shown); the rollers X^4 moving past the cam blocks X^6 . Owing to the action of the spring X^{12} , however, the shaft X^8 and its crank X^7 also return into the position shown, the rollers X^4 again falling into the recesses in the blocks X^6 , whilst the toggle mechanism X^{14} is reset. The switch is now in condition for reclosing when desired.

The shaft X^2 carries a crank Y which is connected by a link Y^1 to one arm Y^2 of a two-armed lever pivoted at Y^3 . The other arm Y^4 of this lever carries at its end a pin Y^5 engaging in a slot Y^6 in the contact arm Y^7 of an auxiliary change-over switch, this arm Y^7 being pivoted at Y^8 . The contact arm Y^7 cooperates with fixed auxiliary switch contacts Y^9 Y^{10} . The contact arm Y^7 and one of the fixed contacts Y^9 are connected to plugs indicated at Y^{11} carried by the draw-out portion and cooperating with sockets in the fixed portion, these sockets being connected to leads Z Z^1 . The other fixed contact Y^{10} may be used for example for indicating purposes. It will be seen that the leads Z Z^1 are connected together through the contact arm Y^7 when the main switch is open, the circuit being broken when the main switch is closed.

The lead Z is connected through a selecting control switch Z^2 to one of two control busbars Z^3 , whilst the lead Z^1 passes to the solenoid S_2 , which controls the pivoted arm S (Figures 9 and 10), and thence to the other control busbars Z^4 . The selecting control switch Z^2 is provided with a number of contacts, one associated with each of the switches to be controlled. Another lead from the control busbar Z^3 passes to the contact arm Z^5 of a change-over switch which cooperates with fixed contacts Z^6 and Z^7 . The contact Z^6 is connected through the toggle-controlling solenoid Q^7 (Figure 9) and through a control switch Z^8 to the other busbar Z^4 , this switch Z^8 being so interlocked with the switch Z^2 that it cannot be closed unless the switch Z^2 is closed. The other contact Z^7 is connected to the busbar Z^4 through the motor O and the coil of the friction brake O^1 in parallel to one another. The auxiliary switch Z^5 Z^6 Z^7 is operated through suitable mechanism by the toggle levers Q^5 and by the motor crank O^5 , so that when the toggle Q^5 is broken the contact arm Z^5 will be moved over from the position shown into engagement with the contact Z^7 , whilst when the motor crank O^5 has com-

pleted its cycle the auxiliary switch will move back to the position shown.

A suitable mechanism for operating the auxiliary switch Z^5 Z^6 Z^7 is shown in Figure 9, the contact arm Z^5 being mounted on a spindle Z^8 carrying two lever arms Z^9 Z^{10} . The arm Z^9 is connected through a link Q^8 to a pin Q^9 which can move in a slot Q^{10} in a plate Q^{11} rigidly connected to the two-armed lever Q^4 . The arm Z^{10} is connected through a link O^7 to a pivoted catch O^8 whose finger O^9 cooperates with a pin O^{10} on one of the gear wheels O^4 . Thus when the toggle Q^5 is broken, the movement of the plate Q^{11} causes the contact arm Q^5 to move over into engagement with the contact Z^7 . This brings the finger O^9 on the catch O^8 into the path of the pin O^{10} . When the toggle Q^5 is reset the slot Q^{10} in the plate Q^{11} moves past the pin Q^9 without affecting the contact arm Z^5 . When the motor cranks O^5 are just about to complete their cycle, the pin O^{10} engages with the finger O^9 and thereby acts through the link O^7 to bring the contact arm Z^5 back into engagement with the contact Z^6 and also moves the pin Q^9 to the other end of the slot Q^{10} ready for the next operation.

The electrical circuits diagrammatically indicated in Figure 13 are shown in the condition corresponding to the open position of the main switch. When it is desired to close the main switch, the selecting control switch Z^2 is moved into the appropriate position. This completes the circuit (through the auxiliary switch contact arm Y^7) to the solenoid S^2 which thereupon lifts the arm S into the operative position. The control switch Z^8 is then closed. This completes the circuit to the solenoid Q^7 which breaks the toggles Q^5 Q^6 and thus releases the spring to close the switch thereby deenergizing the solenoid S^2 . The breaking of the toggles Q^5 Q^6 causes the auxiliary switch contact arm Z^5 to move over into engagement with the contact Z^7 , thus deenergizing the solenoid Q^7 , releasing the brake O^1 and starting up the motor O . This lifts the spring barrel P^1 to reset the spring and also to reset the toggles O^5 O^6 . As the spring barrel P^1 approaches its bottom position, the auxiliary switch Z^5 Z^6 Z^7 is changed over to stop the motor and apply the brake (the control switch Z^8 meanwhile having been opened). The apparatus is now ready for further switch actuation when required.

It will be appreciated that although the various arrangements have been described with reference to the operation of one selected switch, they are equally applicable to the case when two or more selected switches are to be simultaneously operated. Thus when the switches are operated from a common motor either directly or through a common energy-storing device, the simultaneous actuation of two or more of the selecting

solenoids (instead of one as described) will allow the simultaneous closing of the corresponding switches. Again in the case where each switch has its own energy-storing device, two or more of such devices may be simultaneously released to close the corresponding switches, and these devices may be simultaneously re-energized by the common motor.

10 It will be understood that the various arrangements more particularly described have been given by way of example only and that modifications may be made without departing from the scope of the invention. Thus, 15 for instance, other forms of energy-storing devices may be employed instead of springs such as falling weights. Again the power for setting the energy-storing devices or for directly operating the switches may be obtained from a source other than an electric motor, and in some cases it may be desirable to set the energy-storing devices by hand.

What we claim as our invention and desire to secure by Letters Patent is:—

25 1. In electric switchgear, the combination of a plurality of oil-immersed switches, an actuating mechanism for each switch, an electric motor, a common driving member for the actuating mechanisms, a device for storing energy received from the electric motor, means whereby the energy released from the energy-storing device is utilized to drive the common driving member, and means for selectively bringing the actuating mechanisms 30 into operative engagement with the driving member.

40 2. In electric switchgear, the combination of a plurality of oil-immersed switches, an actuating mechanism for each switch, an electric motor, a common driving member for the actuating mechanisms comprising a longitudinally movable bar, means whereby power derived from the electric motor is utilized to move the bar longitudinally, a plurality of arms pivoted to the longitudinally 45 movable bar and associated one with each switch, and means whereby the arms can be selectively moved into operative engagement with the individual switch-actuating mechanisms.

50 3. In electric switchgear, the combination of a plurality of oil-immersed switches, an actuating mechanism for each switch, a driving unit, a common driving member for the actuating mechanisms comprising a longitudinally movable bar, a device for storing energy received from the driving unit, means whereby the energy released from the energy-storing device is utilized to move the bar longitudinally, a plurality of arms pivoted to the longitudinally 60 movable bar and associated one with each switch, and means whereby the arms can be selectively moved into operative engagement with the individual switch- 65 actuating mechanisms.

4. In electric switchgear, the combination of a plurality of oil-immersed switches, an actuating mechanism for each switch, a driving unit, a common driving member for the actuating mechanisms, means whereby power derived from the driving unit is utilized to 70 drive the common driving member, a plurality of selecting electromagnets one for each switch, and a device associated with each electromagnet and acting when operated thereby to bring the common driving member into operative engagement with the corresponding switch-actuating mechanism whereby movement of the common driving member will cause the closing of the selected 75 switch.

5. In electric switchgear, the combination of a plurality of oil-immersed switches, an actuating mechanism for each switch, a driving unit, a common driving member for the actuating mechanisms, a device for storing energy received from the driving unit, a plurality of selecting electromagnets one for each switch, means associated with each electromagnet whereby when the electromagnet is energized the common driving member is brought into operative engagement with the corresponding switch-actuating mechanism, and means for releasing the energy from the energy-storing device to drive the common driving member and thereby to close the selected 85 switch.

6. In electric switchgear, the combination of a plurality of oil-immersed switches, an actuating mechanism for each switch, a driving unit, a longitudinally movable bar common to all the actuating mechanisms, means whereby power derived from the driving unit is utilized to move the bar longitudinally, a plurality of arms pivoted to the bar and associated one with each switch, and an electromagnet associated with each arm and acting when energized to move the arm into operative engagement with the corresponding switch-actuating mechanism.

7. In electric switchgear, the combination of a plurality of oil-immersed switches, an actuating mechanism for each switch, a common driving member for the actuating mechanisms, a spring, means for stressing the spring and holding it in its stressed condition, means for releasing the spring whereby it can drive the common driving member, and means for selectively bringing the actuating mechanisms into operative engagement with the common driving member.

8. In electric switchgear, the combination of a plurality of oil-immersed switches, an actuating mechanism for each switch, a longitudinally movable bar common to all the actuating mechanisms, a spring, an operative driving connection between the spring and the bar means for stressing the spring and for holding it in its stressed condition, electro-magnetically-operated means for releasing 125 130

the spring whereby the bar is moved longitudinally, and electromagnetically-operated means for bringing the longitudinally movable bar into operative engagement with a selected switch-actuating mechanism.

9. In electric switchgear, the combination of a plurality of oil-immersed switches, an actuating mechanism for each switch, a longitudinally movable bar common to all the actuating mechanisms, a spring, an operative driving connection between the spring and the bar, an electric motor serving to supply the power for stressing the spring, a toggle mechanism for holding the spring in its stressed condition, an electromagnet for collapsing the toggle mechanism and thereby releasing the energy stored in the spring to move the bar longitudinally, a plurality of arms pivoted to the bar and one associated with each switch, and a selecting electromagnet associated with each arm and acting when energized to move the arm into operative engagement with the corresponding switch-actuating mechanism.

10. In electric switchgear, the combination of a plurality of oil-immersed switches, a driving unit common to all the switches, a device for storing energy received from the driving unit, means for holding the energy stored in the device, means for releasing the stored energy whereby the switches are selectively closed, and means whereby after the closing of a selected switch the driving unit is caused to reset the energy-storing device ready for further switch-closing.

11. In electric switchgear, the combination with the features set forth in claim 1 of auxiliary switch mechanism whereby after the operation of a selected switch the electric motor is caused to reset the energy-storing device ready for further switch-actuation.

12. In electric switchgear, the combination with the features set forth in claim 5, of auxiliary switch mechanism acting when 5 a selected oil-immersed switch is closed to break the circuit to the corresponding selecting electromagnet and to make a circuit which causes the driving unit to reset the energy-storing device ready for further 0 switch-actuation.

13. In electric switchgear, the combination of a plurality of oil-immersed switches, an electric motor common to all the switches, a device for storing energy received from the 5 electric motor, means for holding the energy stored in the device, electromagnetic means for selecting an individual switch and for releasing energy from the energy-storing device to close the selected switch, auxiliary 10 switch mechanism acting when the selected switch is closed to de-energize the electromagnetic selecting and energy-releasing means and to make a circuit which causes 15 the electric motor to reset the energy-stor-

ing device ready for further switch-actuation.

14. In electric switchgear, the combination of a plurality of oil-immersed switches, an electric motor common to all the switches, 70 a device for storing energy received from the electric motor, means for holding the energy stored in the device, electromagnetic means for selecting an individual switch and for releasing energy from the energy-storing 75 device to close the selected switch, control switch mechanism operable at will for controlling the circuits to the electromagnetic selecting and energy releasing means, and auxiliary switch mechanism automatically 80 operated after the operation of a selected switch to break such circuits.

15. In electric switchgear, the combination with the features set forth in claim 9, of control switches operable at will for controlling the circuits to the toggle-controlling 85 electromagnet and to the selecting electromagnets, and auxiliary switches automatically operated when a selected switch is closed to break such circuits and to make a 90 circuit to the electric motor whereby the motor is caused to reset the spring.

In testimony whereof we have signed our names to this specification.

FRANK COATES. 95
JAMES MIRREY.
